CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

INSULATOR.

1,259,383.

Specification of Letters Patent. Patented Mar. 12, 1918.

Application filed May 11, 1914. Serial No. 837,742.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Insulators, of which the following is a specification.

My invention relates to electrical insulating bodies or structures, and particularly to such structures as are employed for supporting high-voltage lines or conductors.

I have discovered that, if the electrostatic flow lines in fields external to insulating bodies are precluded from concentrating upon their surfaces, the insulating structures are capable of effectively insulating conductors of extremely high potentials. In order to provide insulating structures of the most efficient design, it is necessary to consider the application of the insulating materials, and also the production of substantially uniform electrostatic fields in the regions external to the structures. Accordingly, the maximum insulating strength of structures may be obtained if the external electrostatic fields are so distributed as to create uniform surface stresses upon the insulating structures.

30 A desirable form of a transmission line insulating support comprises a system of condensers connected in series relation. It is highly desirable to obtain equal divisions of potential difference between the insulating units comprising the condensers, but this is not the only requirement of a successful design. The aforementioned condition may actually be obtained, and yet the system of insulators will break down at a very much 40 lower potential difference than the sum of the breakdown strengths of each insulator. To increase the strength of the system, the external electrostatic field should be so distributed as to secure a substantially uniform 45 surface distribution of the electrostatic stresses imposed thereupon, as above mentioned. The external field will then be substantially uniform and agree with the division of potential between the individual insulators or condensers. The efficiency of the 50 combination is thereby increased in exactly the same way that the efficiency of a condenser-type bushing of a particular design is increased by the addition of a large disk, 55 namely, because it completes the surface dis-

tribution of the electrostatic field in the region surrounding the bushing.

It is unnecessary, however, to so design an insulating support as to effect an equal division of the potential difference between 60 the various units comprising the support in order to obtain good results, inasmuch as a substantially uniform distribution of the electrostatic field surrounding the support greatly enhances the insulating value of the 65 support. Of course, when it is preferred to have the most efficient design and to minimize the overall length of the structure, it is desirable, for maximum efficiency, that the 70 external field be substantially uniform and agree with the division of potential between the individual insulators comprising the structure.

One object of my invention is to provide 75 an insulating structure for electrical conductors that shall be simple in construction, and that shall substantially preclude the concentration of electrostatic stresses upon the surfaces of the structure.

Another object of my invention is to provide 80 an insulating structure for electrical conductors that, for a given voltage, will be of smaller dimensions than heretofore utilized in structures adapted for a similar voltage, or that, for a given size, may be 85 capable of withstanding higher voltages than insulators not provided with my invention.

For a better understanding of the nature, 90 scope and characteristic features of my invention, reference may be had to the following description and the accompanying drawing in which Figures 1 and 2 are sectional and side elevational views, respectively, of insulating supports equipped with devices built in accordance with my invention, and 95 Figs. 3 and 4 are similar views of suspension type insulators embodying forms of my invention.

In Fig. 1, a high-potential conductor 1 is secured, by means of a clamping device 2, to 100 an insulating support 3 which engages a pin 3^a. The support 3 comprises a series of insulators or condensers 4 superposed upon one another, the upper and lower members 5 and 6 of which are provided with discoidal 105 shaped electrodes or conducting members 7 and 7^a that extend laterally beyond the insulators 4.

Each insulator 4 comprises a metal bell or 110 Petticoat 8 into which is molded an insulat-

ing compound 9. A recess 10 is provided in order that the adjacent bell may be nested therein, substantially as shown. The surface 11 of the dielectric or insulating compound 9 which is intercepted between two adjacent bells, is so molded as to conform to the lines of force of the electric field between the two adjacent bells. For the most economical design, it is desirable to have each insulator 4 take up approximately an equal share of the difference of potential between the conductor 1 and the structure from which the conductor is to be insulated.

In order to obtain the highest efficiency, the discoidal-shaped electrodes 7 and 7^a are supplied to approximate the result which would be obtained by bounding the insulating support 3 by two infinite parallel conducting planes perpendicular to the axis of the insulator. By means of the electrodes or conducting members 7 and 7^a, the electrostatic field external to, and surrounding, the insulating structure 3, will be substantially uniform. The condition for equal division of potential between the units 4 of the insulating structure is that the flux leaving each electrode or metal bell 8 shall be of the same quantity; this means that the capacity of each electrode 8 to ground must be inversely as its potential, and that the capacity between adjacent pairs of electrodes 8 must be equal. This is approximated very closely if the high potential electrode 5 and the ground or low potential electrode 6 coincide at their edges with the laterally-extending or flux-distributing surfaces of the discoidal bodies 7 and 7^a, respectively.

An insulator made according to the above plan conforms to the law of uniform fields, and is insured against concentrations of electrostatic stresses upon its surfaces. Again, if the dimensions of the insulating structure as shown, are doubled, the capacity of the insulating structure to resist high potentials is doubled.

It is apparent, however, that, by the application of discoidal shaped bodies 7 and 7^a to types of insulating supports other than the one shown in Fig. 1, as, for example, the support shown in Fig. 2, the insulating strength of the support is greatly enhanced. The conductor 1 in Fig. 2 is supported by any adequate means upon the insulating structure 12 which comprises a plurality of superposed porcelain insulators 13 of a well known type. The discoidal shaped bodies 7 and 7^a are supplied to the upper and lower portions of the support 12 in order to effect a substantially uniform distribution of the electrostatic field surrounding the support 12 and to thereby preclude concentration of electrostatic stresses upon the surfaces thereof.

In Figs. 3 and 4, I have shown my invention applied to suspension type insulators.

The structure shown in Fig. 3 comprises a plurality of members 14 having substantially spherical top portions 15 and bottom portions 16 that extend laterally therefrom. Rods 17 having enlarged ends 18 which project into the spherical portions 15, are provided in order that the members 14 may be superimposed upon one another, as shown. The lower ends of the rods 17 are provided with hooks 19 which engage eyelets 20 formed in the top portions of an adjacent conducting member 16. To securely hold the rods 17 in place, the insulating compound or dielectric 9 is molded around the top portion 18 of the rods, and the exposed surface 11 is preferably molded to conform to the electrostatic flow lines between the adjacent conducting members 16. In order to disengage the hook 19 from a coöperating eyelet 20, it is desirable to provide a recess 21 in the molded material. The recess 21 will not affect the insulating properties of the structure.

In this instance, a high potential conductor 22 is suspended from a clamping device 23 disposed on the lower end of a rod 24 secured to a lower conducting member 25. The conducting member or electrode 25, in coöperation with an upper conducting member or electrode 26, is provided with laterally extending portions 27 and 28, respectively. The whole is suspended from a hook 29 attached to any suitable supporting tower, pole, etc. (not shown). The electrodes 25 and 26 serve in this structure for the same purpose that the electrodes 7 and 7^a served in the structures shown in Figs. 1 and 2, and, what is said relative to the most efficient design of the structure in Fig. 1, may be applied with equal effectiveness to the most efficient design of a structure to be made in accordance with the device shown in Fig. 3.

In Fig. 4, the insulators 14 have been replaced by porcelain suspension type insulators 30 of a well known type of construction. While the device shown in Fig. 4 is not as efficient in resisting potential stresses as the device shown in Fig. 3, it has, however, very high insulating properties which are greatly enhanced by the addition of electrodes 26 and 27.

Although I have shown and described devices of specific structural details, many modifications may be effected therein within the spirit and scope of my invention, and I desire that only such limitations shall be imposed as are indicated in the appended claims.

I claim as my invention:

1. The combination with an insulator comprising a plurality of superposed separate units, of conducting members secured to the upper and lower portions thereof, said members having laterally extending flux-dis-

tributing surfaces that coincide with the lower edges of the upper and lower units of said insulator in order to produce a substantially uniform surface distribution of the electrostatic stresses imposed thereupon.

2. The combination with an insulator comprising a plurality of superposed separate units, of parallelly disposed conducting members laterally extending beyond the insulator and secured to the upper and lower portions thereof, the laterally extending surfaces of said conducting members lying in the same planes as the lower edges of the upper and lower units in order to effect a substantially uniform distribution of the electrostatic field surrounding the insulator.

3. The combination with an insulator comprising a plurality of superposed and separate insulating units, of parallelly disposed and laterally extending discoidal shaped electrodes for the upper and lower portions of the insulator, the flux-distributing surfaces of said discoidal shaped electrodes lying in the same planes as the lower edges of the upper and lower insulating units in order to preclude substantially the concentration of electrostatic stresses upon the surfaces of the insulator.

4. The combination with an insulating structure comprising a series of superposed insulating members, of conducting extensions for the upper and lower members that extend laterally beyond said members and lie in the planes coinciding with the lower edges of said members in order to effect a uniform surface distribution of the electrostatic field in the region surrounding the said insulating structure.

5. An insulating support for an electrical conductor comprising a built-up column of insulating members, and laterally-extending electrodes for the upper and lower members thereof, said electrodes being of relatively wide extent in order to produce a substantially uniform distribution of the external electrostatic field wherein it agrees with the division of potential between the insulating members comprising said built-up column.

6. An insulating support comprising a plurality of separate units arranged one above the other and constituting a system of condensers connected in series relation, and means to effect a substantially uniform distribution of the external electrostatic field surrounding the superposed units.

7. An insulating support for an electrical conductor comprising a plurality of separate and similar units arranged above one another and constituting a system of condensers connected in series relation, and means to effect a substantially uniform dis-

tribution of the external electrostatic field surrounding the said superposed units in order to obtain a substantially equal division of the potential differences therebetween.

8. An insulating support for an electrical conductor comprising a plurality of separate units arranged above one another and constituting a system of condensers having substantially equal capacities, and means to effect a substantially uniform distribution of the external electrostatic field surrounding the said condensers in order to obtain a substantially equal division of the potential differences therebetween.

9. An insulating support for an electrical conductor comprising a plurality of separate units arranged above one another and constituting a system of substantially equally spaced condensers having substantially equal capacities, and means to effect a substantially uniform distribution of the external electrostatic field surrounding the said condensers in order to obtain a substantially equal division of the potential differences therebetween.

10. An insulator comprising a built-up structure of equally spaced and identical insulating units, and discoidal shaped electrodes extending laterally from the top of the upper insulating unit and from the bottom of the lowest insulating unit in order to provide an external electrostatic field that agrees with the division of potential between the said insulating units.

11. An insulator comprising a built-up structure of equally spaced and identical insulating units, and conducting members extending laterally from the top of the upper insulating unit and from the bottom of the lowest insulating unit, said conducting members severally having flat parallel surfaces that are opposed to each other in order to provide an external electrostatic field that agrees with the division of potential between the said insulating units.

12. An insulating support comprising a series of superposed insulating units, and flat conducting members extending laterally from the top of the upper unit and from the bottom of the lowest unit in order to inclose all of said units in a substantially uniformly distributed external electrostatic field.

In testimony whereof, I have hereunto subscribed my name this 29th day of April, 1914.

CHARLES LE G. FORTESCUE.
